Primary Examiner — Thomas Johannes**CLAIM**

(57) The ornamental design for a conditioning equipment housing, as shown and described.

DESCRIPTION

FIG. 1 is a top, front perspective view of a conditioning equipment housing showing my new design;
 FIG. 2 is a front elevation view thereof;
 FIG. 3 is a rear elevation view thereof;
 FIG. 4 is a left elevation view thereof;
 FIG. 5 is a right elevation view thereof;
 FIG. 6 is a top plan view thereof; and,
 FIG. 7 is a bottom plan view thereof.
 Broken lines are shown herein depict unclaimed subject matter only, and form no part of the claimed design.
